UNITED STATES PATENT OFFICE.

JOHN CHRISTIAN, OF HYDRAULIC, COLORADO, AND LOUIS S. JUDD, OF OAK PARK, ILLINOIS.

TWYER FOR FORGES.

SPECIFICATION forming part of Letters Patent No. 793,350, dated June 27, 1905.

Application filed August 20, 1904. Serial No. 221,543.

To all whom it may concern:

Be it known that we, JOHN CHRISTIAN, residing at Hydraulic, Montrose county, Colorado, and LOUIS S. JUDD, residing at Oak Park, Cook county, Illinois, citizens of the United States, have invented certain new and useful Improvements in Twyers for Forges, of which the following is a specification.

This invention relates to twyers for forges, and refers more specifically to an improved construction of the character referred to particularly adapted for use in connection with blacksmiths' forges.

Among the salient objects of the invention are to provide a construction in which the air-blast is passed through an extended tortuous course of passage, within which it becomes highly heated, so that the blast which reaches the fire is highly heated; to provide a simple, compact, and symmetrical construction of the character referred to composed of few and easily-constructed parts, which may be readily taken apart and assembled; to provide improved means for controlling the blast-outlet whereby the distribution of the blast is controlled and modified to suit varying conditions; to provide means for regulating the volume of the blast entering the twyer; to provide an improved construction which enables the twyer to be readily cleared of ashes and also facilitates the interchanging of different blast-controlling caps employed therewith; and in general to provide a simple and improved construction of the character referred to.

To the above ends the invention consists in the matters hereinafter described, and more particularly pointed out in the appended claims, and the invention will be more readily understood by reference to the accompanying drawings in conjunction with the description, and in which—

Figure 1 is a side elevation of a preferred embodiment of our invention. Fig. 2 is a plan view of the same. Fig. 3 is a plan view of the lower member of the twyer-body and connected nozzle, the upper main body member being removed and parts of the inlet-pipe being broken away. Fig. 4 is a longitudinal vertical sectional view taken on line 44 of Fig.

2 and looking in the direction of the arrows; 50 and Fig. 5 is a transverse vertical sectional view taken on line 55 of Fig. 1, the construction of the setting of the masonry within which the twyer is seated being also indicated.

Referring to said drawings, 1 designates as 55 a whole the usual bed of an ordinary forge, within the central portion of which is seated a twyer, designated as a whole 2, constituting a preferred embodiment of our invention. As shown, said twyer comprises a lower approximately cylindric casting 3, having a vertical axial passage 4, which extends entirely through said lower body, and a convolute passage 5, formed to extend horizontally in the upper portion of said body and opening at its inner 65 end into the axial passage 4, as best indicated at 6 in Fig. 3. For convenience in casting said convolute passage is made open at its upper side and is closed by means of an upper body member 7, which is circular and provided with 70 an axial opening 8, which registers with the axial passage 4, said body member 7 being desirably provided with an annular groove 9 in its under face, which receives the upper edge of the outer wall 10 of the lower body. The 75 partition members 11 and 12, which define the convolute passage 5, are constructed to fit at their upper edges against the under surface of the body 7, so as to form a closed continuous 80 convolute passage.

13 designates an inlet nozzle or pipe desirably cast integral with the lower member 3 and arranged to extend radially therefrom, the inner end of said pipe being arranged to communicate with the entrance end of the 85 convolute passage, as indicated at 14 in Fig. 3. The outer end of said nozzle is desirably made flaring to receive the correspondingly-tapered end of a valve-body, designated as a whole 15, and which will be hereinafter described.

The upper side of the top body 2 of the twyer is made concave, as indicated at 16, and is provided centrally of said concave portion with a circular rabbet or recess 17, within 95 which is arranged to fit a blast-controlling cap 18, which preferably rises to a height approximately coincident with the top surface

of the body 7. In practice we provide a plurality of such caps 18, severally adapted to fit within the upper body and provided with differently-formed outlet-apertures, which apertures serve to determine the shape and to a certain extent the volume of the blast escaping from the twyer. As shown in Fig. 5, the cap 18 is provided at points coincident with the concave surface 16 of the twyer-body with a plurality of radially-disposed outlet-apertures 19, which obviously distribute the blast in a substantially complete circle. As shown in Fig. 2, however, the cap 18 is imperforate at its side, but is provided at its top with a single transverse slot 20, which serves to form a long narrow blast.

As hereinbefore mentioned, the axial aperture 4 extends through the lower body 3 of the twyer, and the lower end thereof is controlled and closed by means of a plug-valve 22, formed upon the end of a lever-handle 23, pivoted between its ends, as indicated at 24, to a suitable bracket 25, mounted upon the under side of the twyer or forge-foundation. A suitable spring 26 is arranged to hold the plug-valve normally in position to stop the end of the passage 4.

The valve 15, hereinbefore referred to, constitutes an auxiliary feature of the twyer and serves to regulate the supply of air passing from the bellows, the nozzle of which is indicated at 27, to the twyer. Describing said valve, it comprises a main tubular body 28, constituting the valve-casing, tapered at one end, as indicated at 29, to fit the inlet-pipe 13 of the twyer and enlarged at its opposite end 30 to receive the bellows-nozzle. Intermediate the length of said tubular body is formed an enlargement or valve-chamber 31, the upper side of which is covered by a removable closure 32, affording access to the chamber. At the intersection of the inlet-passage 33 with the valve-chamber 31 is formed a downwardly and forwardly inclined valve-seat 34, with which is arranged to coöperate a flap-valve 35, hinged at its upper edge, as indicated at 36, to the upper portion of said seat and weighted, so as to tend to close promptly by gravity. 37 designates a valve-controlling lever which conveniently and as herein shown takes the form of a bail, arranged to extend transversely within the valve-chamber, the lower transverse portion of the bail 38 being adapted to engage the outer or back side of the valve-body, while the arm portions 39 thereof are extended upwardly and then at right angles outwardly in axial alinement with each other to form pivot-supports, which extend out through suitable openings 40 in the side walls of the casing. One of said arms 39 is provided with an extension 41, constituting a lever-handle, which is arranged to coöperate with a notched bar or segment 42 to hold the bail in various positions of adjustment. When

the lever-handle 42 is tilted forwardly to its limit of movement in that direction, the bail engages the upper side of the valve-body when in closed position and holds the latter firmly against its seat. When adjusted to various positions of inclination, the valve will be permitted to open varying distances, thereby determining and regulating the rate of escape of air from the bellows.

The arrangement and operation of the twyer and coöoperating parts will be entirely obvious from the foregoing description, but may briefly be stated as follows: As shown clearly in Fig. 5, the twyer-body is seated in the foundation or masonry with its upper surface flush, or approximately flush, with the top surface of the forge-bed and the lower surface exposed at the under side of the forge-bed. The fire is built in the usual way upon the forge-bed, the fuel being piled over and upon the twyer-iron, and it will be obvious that the twyer-body will become highly heated throughout. The blast entering the twyer-body through the inlet-pipe 13 passes through the convolute passage into the axial passage 4 and thence out through the cap 18, being highly heated before it emerges, and therefore reaching the fire as a hot blast. It is found in practice that a hot blast is much more effective for welding and forging purposes and that the iron or steel is not detrimentally affected by the heating in the forge in cases where it would be seriously affected if heated by the use of the ordinary cold-blast forge. The use of caps 18, having various-shaped outlets and interchangeable, is a feature of considerable importance, since it enables the blast to be confined to a small area when so desired or to be distributed over a large area at will. This effects a material saving of fuel in addition to expediting the operation in many cases. The use of the auxiliary valve is important, because, among other reasons, it enables the forge to be operated with a comparatively small amount of air; it controls the blast to such an extent that it does not rush through the twyer-body too fast, and is therefore properly heated, and it causes the bellows to act more uniformly or with lesser fluctuations in the blast.

While we have herein shown and described what we deem to be a preferred embodiment of our invention, yet it will be understood that the details of construction may be modified without departing from the invention, and we do not, therefore, limit ourselves to these details of construction except to the extent that they are made the subject of specific claims.

We claim as our invention—

1. A twyer for forges comprising a two-part metal body separable in a horizontal plane, the upper body being made massive to form a heat-conductor of relatively large capacity, and said members constructed to form a convolute

inleading-passage communicating at its outer end with the exterior of the body and terminating at its inner end in an axial opening extending vertically entirely through the twyer-body, the walls of said convolute passage being in direct contact with the upper massive member so as to receive heat therefrom, an inlet-pipe communicating with the outer end of said convolute passage, a detachable cap let into the upper side of the upper member, controlling the outlet end of said axial passage, and a valve controlling the lower end of said axial passage.

2. A twyer for forges comprising a two-part metal body separable to form upper and lower body members and provided with a vertical axial passage therethrough, the upper member made massive to form a heat-conductor of relatively large capacity, said members constructed to form a convolute inleading-passage between the meeting portions thereof, which terminates in said axial passage and the walls of which are in metallic connection with the upper member so as to receive heat therefrom, a detachable cap provided with openings therein controlling the delivery end of said axial passage, a valve controlling the opposite end thereof, said controlling-cap being seated within the upper surface of the upper body member approximately flush with the top surface of the latter, and said body member being recessed around the upper portion of the cap to expose the lateral openings through the latter.

3. In a twyer for forges, a twyer-body consisting of two main castings separable horizontally to form upper and lower members both of which are of massive construction to form heat-conductors, said body members con-

structed to form a tortuous inleading-passage 40 between their meeting portions which terminates in a vertical passage through said members, a detachable washer-plate applied to the exposed lower end of the lower twyer-body and serving to hold the twyer in position, a 45 lever pivot-support mounted upon said plate, a lever mounted thereon, and a stopper-valve carried by the end of said lever and controlling said vertical passage, substantially as described.

4. In combination with a twyer for forges comprising a metal body provided with a tortuous and extended inleading air-passage and an inlet-pipe communicating therewith, a flap-valve interposed in said inlet-pipe, and means 55 for positively and adjustably limiting the extent of opening of said valve.

5. In combination with a twyer for forges comprising a metal body provided with a tortuous and extended inleading air-passage and 60 an inlet-pipe communicating therewith, a flap-valve interposed in said inlet-pipe, and means for positively and adjustably limiting the extent of opening of said valve comprising an oscillatory bail the arms whereof are pivotally 65 engaged with the side walls of the valve-chamber and the intermediate portion thereof adapted to engage and form a stop limiting the opening movement of the valve, one of said pivot-arms being provided with an extension constituting a lever-handle, and a notched segment with which said lever-handle co-operates.
